UNITED STATES PATENT OFFICE.

JOSEPH WOLFF, OF BROOKLYN, NEW YORK, ASSIGNOR TO SONORA, INC., A CORPORATION OF NEW YORK.

DESIGN FOR A RADIO LOUD SPEAKER.

Application filed April 12, 1924. Serial No. 9,237. Term of patent 7 years.

To all whom it may concern:

Be it known that I, JOSEPH WOLFF, a citizen of the United States of America, residing in the borough of Brooklyn, county of Kings, city and State of New York, have invented a new, original, and ornamental Design for Radio Loud Speakers, of which the following is a specification, reference being had to the accompanying drawing, forming a part thereof.

This figure is a perspective view of a radio loud speaker, illustrating my improved design.

I claim:

The ornamental design for a radio loud speaker, substantially as shown and described.

This specification signed and witnessed this 10th day of April, 1924.

JOSEPH WOLFF.

Witnesses:

LILLIAN M. SCHAFER,
WALTER L. HUDSON.
